COOLING OF RECIPROCATING PISTONS

Application filed April 11, 1928, Serial No. 269,246, and in Switzerland October 17, 1927.

This invention relates to the cooling of reciprocating pistons, more particularly those of internal combustion engines, of the kind in which the cooling medium is caused to circulate through or is injected into the piston itself.

Hitherto a free jet has been arranged within the crank case immediately below the piston or flow and return pipes for the cooling medium connected to the piston and projecting laterally through the crank case have been arranged so as to reciprocate within fixed pipes outside the crank case. With such free jets it was impossible to prevent the cooling medium from leaking into the crank case and the need for stuffing boxes on the fixed pipes in the other arrangement set up stresses which tended to break the reciprocating pipes.

20 The object of the present invention is to provide a simple and efficient arrangement which, whilst having the advantages of both previous proposals, overcomes the disadvantages from which they suffered.

25 According to this invention cooling medium is supplied in the form of a free jet outside the crank case to a pipe connected to the piston cooling chamber and reciprocating with the piston and also projecting outside the crank case.

One construction according to this invention is diagrammatically illustrated by way of example in the accompanying drawing.

The engine illustrated comprises a cylinder 35 *a* containing a piston *e* the cylinder being mounted upon a crank case *b* containing the crank shaft *d* which is connected to the piston by a connecting rod *c*. Cooling medium is supplied to the piston *e* by means of a pipe *f* which reciprocates with the piston and projects laterally through an opening *m* in the wall of the crank case being supported by an arm *l* secured to the crosshead at *k*. The lower end of the pipe comprises a vertical portion *n* having an enlarged mouth or funnel-shaped opening to receive a free jet *g* of cooling medium which is supplied through a nozzle *h* on a supply pipe *i*. The jet *g* and the collector pipe *n* are enclosed within a separate casing *o* and any cooling medium which fails

to enter the collecting pipe or which leaks therefrom escapes from the casing *o* by means of a pipe *p*.

With the arrangement above described any leakage of cooling medium into the crank case is avoided and the reciprocating pipe on the piston is not subjected to any bending stresses.

It will be understood that the discharge or return of cooling water from the piston 60 can be effected in the same way by means of a pipe similar to the supply pipe *f* adapted to reciprocate with the piston and projecting through the crank case into a separate chamber having a discharge or overflow pipe. 65

In the case of double-acting engines the hollow piston rod is employed in the usual manner for the supply and discharge of the cooling medium to and from the piston.

I claim:

1. In a cooling device for a reciprocating engine, a piston having a cooling chamber therein, a supply tube and a drain tube communicating with said chamber and having their free ends disposed outside of the crank case of said engine, an arm extending outside of said crank case and carrying said tubes, said arm being operatively connected to said piston, and a nozzle for directing a jet of cooling medium into the open free end of said supply tube.

2. In a cooling device for a reciprocating engine, a piston having a cooling chamber therein, a supply tube and a drain tube extending through a slot in the crank case of said engine and communicating with said chamber, an arm extending through said slot and carrying said tubes, said arm being operatively connected to said piston, a discharge pipe telescopically connected to the free end of said drain tube, and a nozzle spaced from the free end of said supply tube and adapted to direct a jet of cooling medium thereinto.

In testimony whereof I have affixed my signature.

WERNER TOBLER.
